UNITED STATES PATENT OFFICE.

NELSON O. BILLINGS, OF EUGENE, OREGON, ASSIGNOR OF ONE-HALF TO CASPAR A. BILLINGS, OF ASTORIA, OREGON.

DOOR-LOCK.

1,305,959.

Specification of Letters Patent. Patented June 3, 1919.

Application filed July 10, 1917. Serial No. 179,662.

To all whom it may concern:

Be it known that I, NELSON O. BILLINGS, a citizen of the United States, residing in the city of Eugene, county of Lane, and State of Oregon, have invented certain new and useful Improvements in Door-Locks, of which the following is a specification.

My invention relates to door locks, and more particularly to a combination door lock, the bolt-operating connections of which can be rendered inoperative by a combination mechanism which is controlled by one of the knobs, with means for setting, or locking, said combination mechanism so that the bolt can be manipulated by means of said knob without throwing off the combination.

Another object of my invention is to provide a second door knob having its operating stem or bolt extended into the lock mechanism at another location, whereby the lock-bolt of said mechanism may be operated at all times by means of said second knob.

Other objects and advantages of my invention will be apparent from the following description of one practical embodiment thereof, taken with the accompanying sheet of drawings, in which,—

Figure 1 is a fragmentary portion of a door, with my lock in place therein;

Fig. 2 is an edge view thereof;

Fig. 3 is an inside view of the lock mechanism removed from the door, one of the side plates being removed therefrom;

Fig. 4 is a vertical, sectional view, taken on line 4—4 of Fig. 3, and also showing the bolt operating knobs;

Fig. 5 is a horizontal, sectional view taken on line 5—5 of Fig. 3;

Fig. 6 is an inside elevation of a special tumbler, or disk, forming a part of the combination controlling mechanism; and

Fig. 7 is a sectional view thereof, taken on line 7—7 of Fig. 6.

Referring now more in detail to the drawings, my lock comprises a lock box, or casing, 1, of any desired size, or type, having an edge face plate 2, adapted to be seated flush with the edge of the door D, as clearly indicated in Figs. 1 and 2. Slidably mounted within said lock box, or casing 1, is a lock bolt 3, the inner portion of which is provided with two lug-like shoulders 4—4, provided with holes 5—5. Said bolt 3, is of loop form at its inner end, as clearly indicated in Fig. 3, whereby a coiled spring 6,

can be inserted therein, bearing at one end against said bolt, and at its opposite end against an anchor block 7, whereby said bolt is normally held extended through the face plate 2, as shown. Pivotedly suspended between the side members of said box, or casing, 1, is an operating lever 8, the lower end of which has operating connections, as at 9, with said lock bolt 3. An operating member 10, provided with a square hole 11, to receive the knob bolt 12, is seated between the side plates of said casing 1, and is provided with short and long levers 13 and 14, having bearing rollers 15 and 15', at their ends adapted to bear against said operating lever 8, whereby as said knob bolt 12 is turned by means of its knob 16, said operating member 10 is rocked so that one or the other of its lever portions 13 or 14 swings the operating lever 8 rearwardly, thus drawing the lock bolt 3 inwardly against the tension of the spring 6, no matter which way the knob 16 is turned.

Pivotedly connected to one of the shoulders 4, of said lock bolt 3, is a hook-like member 17, the hooked end of which is adapted to ride upon the edges of three disks 18, 19 and 20, mounted between the sides of the casing 1, and adapted to receive the operating bolt 21 of the knob 22. The outer disk 20, shown in Figs. 6 and 7, is provided with a square hole, whereby it is turned whenever the knob 22 and its bolt 21 are turned. Said disks 18, 19 and 20 are provided, respectively, with notches 18', 19' and 20'. The disk 20 is also formed with a notch, or shoulder, 20^a, as clearly shown in Figs. 3 and 6. Said disk 20 is also provided on its inner face with a transfer knob 20^b, which has an interfitting or transfer engagement with the next adjacent disk 19, and said disk 19 has a similar transfer, or connection, with the disk 18. As these operating connections from one disk to another in a combination mechanism is old, the details thereof need not here be more particularly shown. The disks can be turned to bring their notches 18', 19' and 20' into register with each other at the top of the disks, whereby the hooked member 17, carried by the lock bolt 3, drops into said notches, as shown in Fig. 3. Thus when said knob 22, and said disks are now turned to the right, they operate through said hooked member 17 to draw the lock bolt 3 inwardly into the casing 1, thus allowing

the door to be opened. Should the knob 22 be turned to the left, it turns the disk 20 therewith, whereupon the curved portion of its notch 20', operates to lift the hooked member 17, up on to the edges of said disks and any sufficient turning of said disks will throw off the combination. In order to set said combination against being thrown off, I have provided a pivoted latch 23, the inner end of which engages the shoulder 20^a, of the disk 20, when the outer end 23' of said pivoted latch 23 is raised. To this end said latch projects through the face plate in convenient position to be raised and lowered by the finger, at will. A coiled spring 24, operates to hold said latch 23 in its raised, or lowered, position, as the case may be. It will thus be seen that when said latch is set so that its inner end engages the notch 20^a, in the disk 20, that neither said disk 20 nor the knob 22 can be turned to the left, thus making it impossible to throw off the combination until the latch 23 is moved out of engagement with the notch 20^a. Said knob 22 and said disk 20, however, can be turned to the right, at will, for the purpose of drawing the lock bolt 3 into the casing 1.

Mounted on the shank, or bolt, 21, of the knob 22, is a combination disk 25, which is turned with the knob and its bolt 21 and controls the positioning of the combination disks 18, 19 and 20, in bringing the notches therein into register with each other so as to receive the hooked member 17, as shown in Fig. 3, and hereinbefore described. Said combination disk 25, bears against a face plate 26, which may be mounted upon the side of the door, as shown.

Mounted in the face plate 26, is a miniature electric lamp 27, partially surrounded by a hood 28, on the face plate 26. A small storage battery 29, may be mounted in the lock casing 1, from which the circuit wires 30 and 31 may be extended to said miniature lamp 27, said circuit also including a little press button, or switch, 32, for turning on the circuit for lighting said lamp, which is positioned to show the combination.

A false key lock 33, is also shown, and this may be used for any purpose desired, such, for example, as setting off a burglar alarm in case it is manipulated, but which forms no part of the present invention, and, therefore, is not shown.

Thus it will be seen that I have provided a combination door lock, the lock bolt of which can be manipulated by means of an independent inside knob 16, having operating connections with said bolt, or said bolt can be manipulated by an independent outside knob 22, after the combination mechanisms have been properly set so that the operating hooked member carried by the lock bolt 3, drops into the operating notches 18', 19' and 20' of the combination disks,

as hereinbefore described. I have also provided convenient latch mechanism, whereby the combination mechanism can be set against being thrown off when it is desired to leave the lock so that one may enter from the outside without the necessity of working the combination.

The lock bolt 3, by having two lug-like shoulders 4-4, is reversible, the hooked member 17, being interchangeable from one to the other, as is clearly indicated from the drawings.

I am aware that changes in details can be made in my invention as here shown and described, without departing from the spirit thereof; and I do not, therefore, limit this invention to these details, except as I may be limited by the hereto appended claims.

I claim:

1. A lock of the character referred to comprising a casing, a bolt slidably therein, a spring normally holding said bolt extended through said casing; a bolt moving member pivotally connected at one end to said bolt and at its other end provided with a hook-like portion, a series of combination disks provided with notches to receive said hook-like portion when said notches are in register, a knob with combination mechanism for operating said combination disks, an operating lever above said bolt and connected therewith at one end for moving the same without interfering with the movement of said bolt by said bolt moving member, and a hand knob at a different location in said casing with connections for operating said operating lever and said bolt independently of said first mentioned knob, whereby said bolt can be operated thereby at any time, substantially as described. 105

2. In a door lock of the character referred to, a casing, a lock bolt slidably mounted therein, and adapted at its upper and lower edges to have an operating member pivotally connected therewith; an operating member pivotally connected to the lower edge of said bolt in the same plane therewith; a combination mechanism adapted to be set for automatically connecting with said operating member; a knob connected with said combination mechanism for operating the same and for moving said bolt; an operating member above said bolt and connected therewith, a second knob connected in said casing at a different location and at the opposite side thereof, and adapted to move said bolt when turned in either direction, independently of said combination mechanism and first mentioned knob, and a latch member adapted to be manually set to prevent the turning of said combination mechanism in one direction, whereby said lock can be operated by said combination mechanism and its knob, without throwing off the combination, substantially as described. 110

3. In a door lock of the character referred to, a casing, a lock bolt slidably mounted therein, and adapted at its upper and lower edges to have an operating member pivotally connected therewith; an operating member pivotally connected to the lower edge of said bolt in the same plane therewith; a combination mechanism adapted to be set for automatically connecting with said operating member; a knob connected with said combination mechanism for operating the same and for moving said bolt; an operating member above said bolt and connected therewith, a second knob connected in said casing at a different location and at the opposite side thereof, and adapted to move said bolt when turned in either direction, independently of said combination mechanism and first mentioned knob, and a latch member adapted to be manually set to prevent the turning of said combination mechanism in one direction, whereby said lock can be operated by said combination mechanism and its knob, without throwing off the combination, substantially as described. 120

3. A door lock comprising a lock casing, a lock-bolt slidably mounted therein, a hook-like operating member pivotally connected with the lower edge of said bolt and lying in the same plane therewith, a plurality of axially arranged disks provided with notches in their edges adapted to be moved into register with each other to receive said hooked member, a knob for operating said disks, and said hooked member, for moving said lock bolt, a swinging lever pivoted at its upper end in said casing and connected at its lower end with said lock bolt, a second

knob through said casing, and an operating member connected with said knob and operating against said swinging lever, whereby to move said lock bolt when said knob is turned in either direction, independently of said first mentioned knob, substantially as described.

Signed at Eugene, Lane county, Oregon, this 29th day of June, 1917.

NELSON O. BILLINGS.

In presence of—

GEO. G. DORRIS,
VERA GWIN.
